UNITED STATES PATENT OFFICE.

JABEZ BURNS, OF BROOKLYN, NEW YORK.

GRINDING-MILL.

SPECIFICATION forming part of Letters Patent No. 349,628, dated September 21, 1886.

Application filed December 3, 1885. Serial No. 184,614. (No model.)

To all whom it may concern:

Be it known that I, JABEZ BURNS, a citizen of the United States, residing at Brooklyn, in the county of Kings and State of New York, have invented new and useful Improvements 5 in Grinding-Mills, of which the following is a specification.

This invention relates to a grinding-mill having a reversible bed-stone which is dressed 10 on both faces and provided with trunnions or journals at its circumference.

The object of this invention is to provide novel means for supporting the trunnions or 15 journals and securing the bridge of the mill, whereby the bed-stone can be conveniently and expeditiously reversed.

To such end the invention consists in the construction and combination of devices hereinafter described and claimed, reference being made to the accompanying drawings, in 20 which—

Figure 1 represents a sectional elevation of a grinding-mill provided with a reversible bed-stone. Fig. 2 is a plan or top view of the 25 same. Fig. 3 is a detached face view of one of the boxes which form the bearings for the trunnions of the bed-stone.

Similar letters indicate corresponding parts.

In the drawings, the letter A designates the 30 runner of a grinding-mill, and B is the bed-stone. The runner is firmly mounted upon the vertical arbor C, and the bed-stone is hung on trunnions D D, which have their bearings in boxes E E, which are constructed and secured to the standards G G of the mill-frame, as hereinafter described. The bed-stone is dressed on both faces, and the trunnions extend from its circumference at the middle of its 35 thickness, so that either face of the bed-stone can be brought into the proper working position toward the runner simply by reversing said bed-stone. Of course, in dressing the two faces of the bed-stone, care must be taken to arrange such dressing so that the bed-stone 40 will work correctly, no matter which of its two faces is brought in working position. If the dressing consists of tangential lines, the lines on one face must run in the same direction to those on the other face.

50 In order to facilitate the operation of reversing the bed-stone, the frame of the mill and the boxes E E are so constructed that said parts

can be readily taken apart and replaced without much loss of time. For this purpose the bridge F is secured by means of swing-bolts f f, 55 pivoted at their lower ends to the top portions of the standards G G, and engaging the bifurcated ends of the bridge. The boxes E E are secured to the standards by screw clamping-bolts K K, so that they can be vertically moved 60 to adjust the bed-stone relatively to the runner, and each box is provided with a cover, I, hinged or pivoted at one end to such box, as at f', and having a bifurcated end, f'', with which engages the swing-bolt e, pivoted to the 65 box, and by which the cover is held down. By swinging the bolts f from engagement with the bifurcated ends of the bridge F and removing the latter, and then releasing the locking swing-bolts of the covers I of the boxes, the bed-stone 70 can be removed and replaced in a reversed position, after which the box-covers and the bridge are replaced and secured.

What I claim as new, and desire to secure by Letters Patent, is—

1. A grinding-mill comprising the standards, the runner-stone, journal-boxes secured to said standards and provided with movable covers, locking devices for securing said covers down upon the boxes, the reversible bed-stone having both faces dressed, and provided 75 with journals attached to its circumference at the middle of its thickness, and the bridge detachably secured to the upper ends of the standards, substantially as described. 80

2. A grinding-mill comprising the standards, a runner-stone, journal-boxes secured to said standards and provided with movable covers, the swing-bolts for locking the covers down, the reversible bed-stone having both 85 faces dressed, and provided at its circumference with attached journals, and the removable bridge, substantially as described. 90

3. A grinding-mill comprising the standards, the runner-stone, journal-boxes secured to the standards and provided with hinged covers, locking devices for securing the covers down upon the boxes, the bed-stone provided with journals and dressed upon both faces, the bridge, and the swing-bolts for detachably 95 securing the bridge, substantially as described. 100

4. A grinding-mill comprising the standards, the runner-stone, journal-boxes secured to the standards and provided with movable

covers, the swing-bolts for locking the covers down, the bed-stone dressed upon both faces and having attached journals, the bridge, and swing-bolts for detachably securing the bridge, substantially as described.

5. A grinding-mill comprising the standards, the runner-stone, journal-boxes secured to the standards and provided with movable covers having bifurcated ends, the swing-bolts 10 pivoted to the boxes and engaging the bifurcated ends of the covers, the bed-stone dressed

on both faces and having attached journals, and the removable bridge, substantially as described.

In testimony whereof I have hereunto set my hand and seal in the presence of two subscribing witnesses.

JABEZ BURNS. [L. S.]
